United States Patent Office

Des. 230,397
Patented Feb. 19, 1974

230,397

APARTMENT BUILDING

Bertram Zusman, 570 Madera Ave.,
Youngstown, Ohio 44504

Filed Mar. 12, 1973, Ser. No. 340,055

Term of patent 7 years

Int. Cl. D25—03

U.S. Cl. D13—1 A

FIG. 1

FIG. 2

FIG. 3

FIG. 4

FIG. 1 is a front elevation of the apartment building.
 FIG. 2 is a rear elevation of the apartment building.
 FIG. 3 is an end elevation showing the left end of the apartment building as seen in FIG. 1.

FIG. 4 is an end elevation of the apartment building showing the right end as seen in FIG. 1.

The broken line showing of the foundation in the several views has been disclosed for illustration purposes only and forms no part of the claimed article.

I claim:

The ornamental design for an apartment building, substantially as shown and described.
